UNITED STATES PATENT OFFICE.

LEWIS BEEBEE AND FRANK BOWERS, OF DETROIT, MICHIGAN, ASSIGNEES, BY MESNE ASSIGNMENTS, TO DIAMOND POWER SPECIALTY COMPANY, OF DETROIT, MICHIGAN, A COPARTNERSHIP COMPOSED OF RAPHAEL HERMAN AND SAMUEL J. HERMAN.

BOILER-CLEANER.

1,343,654.

Specification of Letters Patent. Patented June 15, 1920.

Application filed July 21, 1916. Serial No. 110,492.

To all whom it may concern:

Be it known that we, LEWIS BEEBEE and FRANK BOWERS, both citizens of the United States of America, residing at Detroit, in the county of Wayne and State of Michigan, have invented certain new and useful Improvements in Boiler-Cleaners, of which the following is a specification, reference being had therein to the accompanying drawings.

This invention relates to boiler cleaners and refers more particularly to a construction in which rotatable nozzles or other blower units are arranged to blow the soot from the boiler tubes.

Among the objects of the invention are to provide in a boiler cleaner, an automatic blow-off and drainage system; to so construct and arrange the blow-off system that it will prevent the operator from leaving the supply valve open and will insure that the blow-off nozzle or drain pipe will be automatically opened when the nozzles are not in use; to provide a novel construction and arrangement of rotatable blower unit; to provide improved means for supporting the blower units; and in general to provide a new and improved construction of boiler cleaner of the character above described.

The invention also resides in the novel arrangements and locations of the blower units, particularly with reference to the front water leg of the boiler, and in such features of construction and arrangements and combinations of parts as will more fully hereinafter appear.

In the drawings, Figure 1 is a side elevational view showing the boiler cleaning system embodying our invention;

Fig. 2 is a cross section taken just behind the front water leg of the boiler.

Fig. 3 is an enlarged vertical section through the lower front unit.

Fig. 4 is a side elevational view showing one of the branch pipe connections.

Fig. 5 is a detailed sectional view of the automatic drain valve.

Figs. 6 and 7 are fragmentary sectional views on the lines 6-6 and 7-7 of Fig. 1, respectively, looking in the direction of the arrows.

In the drawings A designates the boiler, which in the particular construction shown

is of the horizontal water tube type, there being a plurality of tubes B connected at their ends to front and rear water legs C and D respectively. The upper ends of these water legs are connected by the drum E, while the usual vertical baffles F and F' are employed for compelling the hot gases from the firebox G to completely traverse the water tubes.

For cleaning the soot from the water tubes B, we employ a plurality of blower units H, H', H'', H''' which are connected by a corresponding series of branch pipes I, I', I'' and I''' with the main steam pipe J. The latter near its upper end receives steam from the drum E and is provided with the usual supply valves J'. However in constructions such as above described the operator is liable to leave this valve J open and simply close the valves K, K', K'' and K''' in the various branch pipes. Should these valves in the branch pipes leak, there is danger that the boiler will be flooded with water discharging through to blower units, and also the further objection that unless the drain valve is left open the water or condensation will collect in the blower system.

In the present construction each of these objections are overcome by the automatic blow-off or drain system which is as follows. A drain pipe line L is connected by various branches M, M', M'', M''' to the valves K, K', K'', K'''. Although this connection could be made to the various branch pipes above the valves, either location is satisfactory providing the valve is interposed between the drain pipe connection and the main steam line. At one end the drain pipe L connects with an automatic type of drain valve L', the latter being preferably a balanced valve which is normally held open by the action of a light spring L'' and closed whenever there is steam pressure in the drain line L.

The operation of the automatic blow-off system, as above described, is as follows. The main supply valve J being opened, steam will pass into the main steam pipe J and as the valve L' is normally opened, the steam will blow off through the drain pipe L'. If there is any water or condensation in the pipes, it will be forced out through the drain pipe, thus insuring a supply of

dry steam to the various blower units H , H' , H^2 , H^3 . These units are generally operated successively from the front to the back so that the blower H^3 or H^2 being first opened would discharge steam through its nozzle. When however the valve H^2 together with the other blower unit valves are all closed, this would remove the pressure from the balanced valve L' and allow the latter to automatically open communication to the drain pipe. The same action would take place with each of the other blower units, the arrangement being such that whenever any of the units are in use the drain pipe connection will be closed or whenever the blower units are shut off from the main steam line, the latter will be in open connection with the drain pipe. Therefore if the operator neglects to close the valve J when the blower unit valves are all closed the steam will blow off through the drain pipe, calling his attention to the fact that the valve J should be closed.

It will be noticed that the units H^2 and H^3 are located directly behind the front water leg, and in case either or both of these units are located in these positions, the following mounting for such units is employed. Describing first, the mounting for the unit H^2 , this unit is supported by clips O secured by U-bolts O' to one of the pipes B . The number and spacing of these clips will, of course, depend upon the length of the blower unit and owing to the closeness of the unit to the firebox, an extension P' of the front supporting wall P is employed for deflecting the heat away from this unit, the construction of such wall being shown in detail of Fig. 3.

If the unit H^3 is employed, a mounting such as shown in connection with the unit H^2 would be impracticable, owing to the inaccessible location of the unit. As shown in Fig. 1, the unit H^3 is positioned about half way between the top and bottom rows of the boiler tubes B , and the staggered relation of the latter as shown in Fig. 2 prevents a direct support being extended downward to the blower unit. To overcome this difficulty a diagonal support Q is employed which at its upper end is secured by a U-bolt Q' and at its lower end is provided with a hook Q^2 which extends beneath and supports the blower unit. It will, of course, be understood that there are as many of these supports Q employed as are necessary to properly support the blower unit H^3 . Moreover, while this type of support is particularly adapted to a unit located in the position of the unit H^3 , it is not necessarily limited to such use.

At their outer ends the various units are provided with the usual operating wheels or

sprockets R . The latter are fixed to the rotatable nozzle pipes S , an extension of which pipe extends into a head S' on the goose-neck S^2 . For preventing longitudinal movement of the nozzle, it is provided with a flange R against which rests a brass ring T upon the opposite side of which is a packing R^2 . For preventing the escape of steam at the joint between the rotatable pipe and the head S' , the packing R^2 is clamped between the ring T and the circular flange U' on the packing gland U . The latter is secured to the head S' by locking bolts or screws V which can be adjusted to advance the gland toward or from the header whenever necessary. The usual supporting bracket W is employed for fastening the unit to the casing W' . The invention however is not limited to the details of construction shown and described except as specified in the appended claims.

What we claim as our invention is:

1. In a boiler cleaner, the combination with a plurality of blower units, a main steam supply pipe for said units, connections between said supply pipe and units, control valves for said connections, a main shut-off valve for said steam supply pipe and means controlled by the operation of said valves for automatically indicating when the main supply valve is left open and the valves in the branch connections closed.
2. In a boiler cleaner, the combination with a steam supply pipe, of a plurality of blower units, branch connections between said supply pipe and blower units, valves in said branch connections, a valve in said steam supply pipe, a drain connection for said pipes and a valve controlling said drain connection automatically held open when the valves in said branch pipes are all closed.
3. In a boiler cleaner, the combination with a plurality of blower units, of a main steam supply pipe, a shut-off valve for said pipe, branch connections between said pipe and said blower units, an auxiliary pipe connected to said branch connections, valves interposed between the main steam supply pipe and said auxiliary pipe, a drain pipe leading from said supply pipe, a normally closed valve for said drain pipe and a connection between said auxiliary pipe and said valve for automatically closing the latter when steam is admitted to any of said blower units.
4. The combination with a boiler, including spaced headers, substantially horizontal water tubes connecting said headers, a substantially vertical baffle spaced from one of the headers, a combustion chamber below the tubes and arranged so that the gases from the combustion chamber pass upwardly intermediate said baffle and said

header, of a blower unit located beneath the water tubes behind and in close proximity to the inner wall of said header, and a protection or guard for said unit positioned 5 directly therebeneath.

5. The combination with a boiler, including spaced headers, substantially horizontal water tubes connecting said headers, a substantially vertical baffle spaced from one 10 of the headers, a combustion chamber below the tubes and arranged so that the gases from the combustion chamber pass upwardly intermediate said baffle and said

header, of a blower unit extending transversely of the water tubes, said unit being 15 located behind and in close proximity to the lower end of the inner wall of said header, and a supporting wall for said header having a portion forming a protection or guard for said unit, positioned directly there beneath. 20

In testimony whereof we affix our signatures.

LEWIS BEEBEE.
